DRINKING STRAW

Milton Dinhofer, New York, N. Y.

Application November 29, 1950, Serial No. 13,184

Term of patent 14 years

(Cl. D2—3)

To all whom it may concern:

Be it known that I, Milton Dinhofer, a citizen of the United States of America, residing in the Borough of Manhattan, city of New York, county of New York, and State of New York, have invented a new, original, and ornamental Design for a Drinking Straw, of which the following is a specification, reference being had to the accompanying drawing, forming part thereof.

I claim:

The ornamental design for a drinking straw, as shown.

MILTON DINHOFER.
